CANE PILER

Samuel A. Thornton, Jeanerette, La., assignor to Samuel A. Thornton, Jr., Alexandria, La.

Application June 9, 1954, Serial No. 435,440

8 Claims. (Cl. 214—9)

The present invention relates to a cane piler, and more particularly, to a machine for use in cane fields which lifts and rolls cut cane into a pile and accommodates loading of the piled cane into a truck or the like for removal thereof from the field.

It is common practice today in the cane fields to pile cut cane by hand or by some form of cane piler, either mule drawn or mechanically powered, and to employ mechanical cane loaders comprising, for instance, a grapple and some type of power hoisting and positioning means therefor to load the piled cane into waiting trucks or the like for removal from the fields. At present, there are two types of mechanical cane pilers in use, one of which pushes cane into a pile as a bulldozer would push earth into a pile, and the other of which employs endless sprocket chains having protruding lugs which engage the cane. The bulldozer type of cane piler, in exerting a straight forward pushing action on the cane, pushes and piles large quantities of cane trash, dirt and/or mud into and with the pile of cane, which is highly objectional. When the field is wet or muddy, the wet, muddy cane trash and large quantities of mud piled with the cane are picked up with the cane and transported to the mill, which is a further objection to the bulldozer type piler. The endless chain type of piler suffers substantially the same disadvantages, so that neither type of piler heretofore available has been fully satisfactory.

In distinction to the foregoing, I have conceived that a cane piler which provided means for lifting cut cane into a pile, rather than pushing it into a pile, would not dig into the ground and would not pick up cane trash, dirt and mud with the cane, thus obviating the disadvantages of known cane pilers.

It is an object of the present invention, first, to provide an improved cane piler affording the novel functions of lifting and rolling cut cane into a pile.

It is another object of the invention to provide a cane piler comprising a vehicle carrying a plurality of generally rectilinear, parallelly disposed, kicker bars positioned to engage cut cane on motion of the machine toward the cane, wherein the kicker bars are effective to lift and roll the cut cane into a pile without digging into the ground.

It is still another object of the invention to provide a cane piler comprising a vehicle carrying a plurality of reciprocating kicker bars positioned to engage cut cane on motion of the vehicle toward the cane, wherein the leading edges of the bars are notched, and wherein the bars engage the cane only on upward movement thereof.

Another object of the invention is to provide a mechanism for imparting a curvilinear, generally vertical reciprocating movement in a plurality of vertically disposed kicker bars, wherein certain of said bars always move in opposition to the remainder of the bars.

Still another object of the invention is to provide a cane piler mechanism including a plurality of substantially vertically disposed kicker bars wherein the bars are

2

so actuated that they not only reciprocate in a vertical direction, but they also move in groups toward and away from the cane being piled, said different groups of said bars alternately engaging the cane only on forward upward motion thereof.

According to the present invention, I provide a cane piling machine comprising a vehicle carrying a plurality of substantially vertically disposed, rectilinear kicker bars positioned to engage cut cane on motion of the machine toward the cane. The bars are mounted for a curvilinear, generally vertical, reciprocating movement and have the leading edges thereof notched, said notched edges engaging the cut cane as the machine moves forward toward it. A rotating drive shaft is provided with a plurality of throws, half of which are set at 180 degrees with respect to the other half, and the throws are connected, respectively, with the respective kicker bars for actuation of the same. An endless flexible connector comprising a belt or chain extends between the drive shaft and a power source. Alternatively, power may be derived from the traction means or a power take-off shaft of the vehicle. The drive or crank shaft is thus rotated and the throws of the drive shaft reciprocate the kicker bars up and down while at the same time move them toward and away from the cane, as the machine approaches the cane. The arrangement is such that the notched kicker bars do not dig into the ground and engage only the cane alternately in groups and only on upward forward motion of the respective kicker bars so that the cane is rolled and lifted into a pile.

From the foregoing, it will be appreciated that the present invention provides substantial advantages over prior practices. For example, the present invention provides a cane piler which piles cut cane with a rolling lifting motion, rather than by just pushing it across the ground, without accumulating dirt and trash with the cane.

In addition to the foregoing, it is an object of the present invention to provide a cane piler which is economical of manufacture and convenient in use.

Other objects and advantages of the present invention will become apparent in the following description of a preferred embodiment of the present invention and the preferred use thereof.

Now, in order to acquaint those skilled in the art with the present invention and with the manner of making and using the same, I shall describe, in connection with the accompanying drawings, a preferred embodiment thereof.

In the drawings:

Figure 1 is a somewhat diagrammatic side elevational view of a combined cane piler and loader;

Figure 2 is a plan view of the cane piler and loader shown in Figure 1;

Figure 3 is a side elevational view similar to that of Figure 1, only on a larger scale showing more particularly the elements comprising my improved cane piler mechanism;

Figure 4 is a rear elevational view of the invention, some parts thereof being omitted for clarity of illustration, showing the kicker bars in a different position to better illustrate the piler drive shaft crank arms;

Figure 5 is a rear elevational view of the invention, similar to that of Figure 4, but on a smaller scale, and

Figure 6 is a side elevational view similar to that of Figure 1, but on a larger scale, illustrating a cane loading apparatus in inclined position for cooperation with the piler mechanism, and indicating several of the other positions (in dotted lines) which the various elements of the apparatus may assume with respect to each other.

Referring now to the drawings, and more particularly

Figures 1 and 2, reference numeral 10 generally indicates a preferred embodiment of the invention, operating under typical conditions in a cane field. The cane 12 ordinarily is grown in parallel rows which extend across a particular cane field and when the cane is cut, it ordinarily falls or is placed across a hollow 13 between the mounds 14, said mounds 14 being built up during the cultivating of the cane while it is growing. As the description proceeds it will become apparent that the invention is fully operable and highly efficient in flat fields as well as the row field illustrated. The cane piler and loader 10 of the illustrated embodiment comprises a conventional tractor 16, or any other suitable vehicle, which carries at one end thereof the piling apparatus 18 and the loading apparatus 20. Such a tractor as is indicated at 16 usually comprises a vehicle having a front portion 22 in which is carried the motor, rear wheels 24, which are usually designated traction wheels since the power from the motor is ordinarily transmitted through them, and front steering wheels 26. The tractor is provided with a conventional steering wheel 28 and supporting body frame 30 of any suitable size and form, and the cane piling and loading apparatus may be mounted at the rear thereof. The driver's seat and other conventional equipment usually accompanying a tractor of this type are not shown as they form no part of this invention. Track-type vehicles, trucks and the like may also be employed if desired.

Secured to the rear of the tractor 16 for operation over and in a hollow 13, in the field illustrated, are a plurality of notched, rectilinear, substantially vertical members 32 which comprise the kicker bars of my piler apparatus 18. Referring more particularly to Figures 3, 4 and 5, it will be seen that a rigid transverse supporting beam 34 is secured in any suitable manner to the body 30 of the tractor and extending rearwardly therefrom substantially over the wheels 24 are substantially horizontal supporting bars 36, with the left hand bar 36 carrying a horizontally disposed rod 38 at the end thereof. Pivoted mounted on the rod 38 are a number of short links 40 (four in the illustrated embodiment) to the ends of which are pivoted the upper ends of the kicker bars 32. An elongate channel beam 42 is mounted transversely of the tractor in any suitable manner, for instance, by the beam 44 extending rearwardly of the tractor (see Figure 2) and mounted in the bearings 46 carried by the beam 44 is a drive shaft 48. Other supporting members for rigidly maintaining the beam 42 in position, such as rigid members 55 depending from bars 36 and the L-shaped member 37 secured between the left hand side of the beam 34, the axle of wheels 24, and the left hand end of beam 42. The support of beam 42, however, is a problem which can be readily solved by those skilled in the art, and the supporting elements indicated are shown for illustrative purposes only. The drive shaft of the illustrated embodiment comprises an elongate rectilinear member 51 having four throws comprising four crank pins 50 and six crank arms 52 formed therein. The rectilinear member, the crank pins, and crank arms are preferably formed in a single unit though the respective elements may be separately formed and later united if so desired. As shown in Figure 4, in the illustrated embodiment two of the throws are disposed on either side of the left hand traction wheel 24 and the outer two of the four throws (with respect to said wheel) are set at 180 degrees with respect to the inner two throws. The lower ends of kicker bars 32 are suitably mounted on the respective crank pins 50 for actuation thereby.

The kicker bars 32, due to the connection above described are adapted to be actuated upon rotation of the crankshaft 48. Rotation may be imparted to the shaft from the vehicle or from a separate power source in any manner desired. For example, in Figures 1 and 2, I have shown somewhat schematically a power take off drive including a chain drive 39 between the shaft 48 and a supplemental, parallelly disposed shaft 41 adjacent the

kicker bars 32, and a chain drive 43 between the shaft 41 and a power take-off 45 from the vehicle engine at the opposite side of the vehicle. In Figures 3 and 4, I have shown a crankshaft drive arrangement derived from the traction means of the vehicle. In this arrangement, the right hand side of the drive shaft has fixed thereto a toothed wheel or sprocket 54, the teeth of which engage an endless flexible chain 56 which leads forwardly to the right hand traction wheel 24 of the tractor (see Figure 3). The outside surface of the flexible chain 56 engages teeth of a toothed wheel or sprocket 58 fixed to the wheel 24 and idler pulleys 60, held in position by a suitable support 62 secured to, for instance, beam 34, hold the outside surface of the flexible chain against the toothed wheel or sprocket 58.

While the illustrated embodiment shows my piler apparatus mounted only on the left side of the vehicle, I comprehend that a similar apparatus could also be carried on the right side or on both sides, that additional kicker bars could be provided on either side, and that the kicker bars could be relocated, with the provision of suitable drive shaft means to actuate the added kicker bars. Thus, another group of kicker bars 32 could be suspended from the right hand support bar 36 in the same manner as described in connection with the left hand bar 36, if so desired. Moreover, the bars 32 could be mounted at other positions on the rear of the vehicle and any number of bars could be employed, depending on the conditions under which the piler is to operate. I also comprehend that other types of drive may be employed to actuate the drive shaft 48, including power take-offs from various portions of the vehicle or a separate power unit, and that eccentric connections may be employed between the kicker bars and the drive shaft. I further comprehend that the piler apparatus may be mounted on the front of a vehicle, if so desired, with suitable modifications being made to the vehicle structure to support the piler apparatus and actuate the mechanism drive shaft.

In use, the cane piler apparatus illustrated and above described is operated, in the field illustrated, by backing the tractor down the mounds 14, with the wheels of the tractor being positioned on each side of a mound (in hollows 13), as shown in Figures 4 and 5. The drive shaft 48 is actuated by the movement of the traction means or power take-off to which it is connected, and rotates in a direction opposite to the direction of rotation of the traction means. Thus, in the embodiment shown in Figure 3, the wheels 24 would be rotating or turning in a clockwise direction as the vehicle moves toward the cut cane 12, and the drive shaft 48 would be rotating in a counterclockwise direction. As the drive shaft rotates, the kicker bars are provided with a curvilinear, substantially vertical, reciprocating movement, in which the lower ends thereof move upwardly as they are brought forward, and move downwardly as they move rearwardly, and follow a path similar to that shown by the dotted line indicated at 64 in Figure 3. Thus, as the vehicle is moved toward the cane and the notched leading edges of one pair of the kicker bars contacts the cut cane, the pair of bars lifts the cane as it is moved forwardly (with respect to the direction of movement of the piler) and then moves away from the cane, at which time the second pair of bars contacts the cane and lifts it upwardly; the result is that the cane is lifted and rolled into a pile as the vehicle moves along.

Once the cane is piled by the cane piling mechanism, it becomes necessary to transfer the cane to a truck or the like, and a cane loader, in the form of a hoist or grab, is normally provided on the tractor 16 to facilitate the transfer. The cane piler mechanism of the present invention may be used with any type of loader, as desired, and the cane piler facilitates the manipulation of the loader by virtue of the neat and clean piling of the cane effected thereby. In the drawings, especially Figures 5 and 6, I have shown a cane loader 20 that I prefer.

Turning now to the loading apparatus 20 shown more particularly in Figures 5 and 6, an upright mast 70 is secured on beam 34 preferably above the center of the left hand traction wheel 24. The mast 70 is mounted on the beam 34 for pivotal movement about a vertical axis passing through its center and through the center of the wheel 24. The mast has an outwardly extending substantially horizontal arm 72 and secured between arm 72 and the beam 34 is a hydraulic cylinder and piston means 74. It will be apparent that as piston rod 76 moves inwardly and outwardly of the cylinder 78, the mast 70 will pivot about its mounting. The arm 72 may assume a suitable configuration so that with the rod 76 pivotally secured to the end thereof, as at 80, the mast may be pivoted through at least an angle of 180 degrees. Two supporting arms 75, connected to sleeve 77 in which the upper end of mast 70 is adapted to oscillate, maintain mast 70 in upright position.

Secured to the lower end of the mast 70 at 81 for pivotal movement about a vertical axis is a telescoping boom 82 which may comprise two or more telescoping elements 83 and 85, and a rigid arm or bar 84 extends between the upper end of the mast 70 and the outwardly projecting end of the boom. The rigid arm or bar 84 is pivotally connected to both of these members at 86 and 88, respectively. The upper end of the boom includes a rigid arm 90 secured to the boom at an angle, and pivoted thereto, intermediate of its ends, is the depending arm 92. A pair of opposed jaws 94 and 96, comprising grapple 98, are pivoted at the lowermost end of the arm 92 and the jaws are adapted to be opened and closed by a pair of hydraulic cylinder and piston means 100 and 102 pivotally secured to the cross bar 104 rigidly mounted on the depending arm 92. As shown in Figure 2, the jaws 94 and 96 each comprise a pair of rigid members 106, 108, and 110, 112, respectively, which are secured together by the rigid bars 114 and 116, respectively. The rectilinear ends of the members 106 and 108 may be joined by a shaft 118, which is pivotally carried at 120 (see Figures 5 and 6) in the lowermost end of the depending arm 92. The rectilinear ends of the members 110 and 112 may be pivotally mounted on the shaft 118, so that the jaw 96 pivots with respect to jaw 94, and both jaws pivot with respect to arm 92, as will be appreciated by those skilled in the art. Secured between the upwardly extending end of the depending arm 92 and the upper end of the boom is a hydraulic cylinder and piston means 122 which is operable to pivot the depending arm 92, and the grapple 98 carried thereby, toward and away from the boom 82. The cylinder and piston means 122 is pivoted at 124 and 126 to allow for relative movement between the depending arm 92 and the boom 82 when the means 122 is operated. As shown in Figure 6, the hydraulic conduits 99 leading to the hydraulic means 100, 102, and 122 are fixed to rigid arm or bar 84 and are directed toward the vehicle proper, and together with the conduit (not shown) from hydraulic means 78 and the conduit 101 leading to the boom 82, they may lead to a source of fluid under pressure provided with the necessary operating valves disposed within reach of the vehicle operator.

In use, swinging movement of the loading apparatus is obtained by operating the hydraulic cylinder and piston means 74 to swing mast 70 about its mounting. The grapple 98 is raised and lowered with respect to the ground by extending and contracting the telescoping elements of the boom 82; thus, hydraulic pressure is applied to the boom, the telescoping elements thereof tend to separate from each other, thus extending the length of boom 82, and the boom moves upwardly about its lower pivotal mounting adjacent the base of mast 70. The grapple is lowered by releasing the hydraulic pressure in the boom, and as the elements of the boom telescope with respect to each other, the boom moves downwardly about said pivotal mounting. The grapple 98

may also be moved toward and away from the boom by operation of the hydraulic means 122 to pivot depending arm 92 about its pivotal connection to the boom.

As shown in Figure 1, the vehicle 10, as it progresses along the mounds 14, brings the kicker bars 32 into engagement with the cane 12 that is disposed across the mounds 14. The kicker bars 32 lift and roll the cut cane into a pile, and when the pile is deemed by the vehicle operator to be large enough for load, the boom 82 and the hydraulic means 122 are operated to position the grapple for the loading operation.

Referring to Figures 1, 2 and 6, the loading apparatus is positioned for the loading operation by moving the boom 82 so that it is substantially parallel with the longitudinal axis of the tractor (though not necessarily parallel to the ground), and therefore, the jaws 94 and 96 are generally perpendicular with respect to the cane being piled. The hydraulic means 122 is also operated to swing the depending arm 92 toward the boom to dispose the arm 92 and the grapple jaws at a low angle of inclination to the ground, with the jaws 94 and 96 being spread to the wide open position through operation of the hydraulic means 100 and 102. The boom is then moved to a substantially horizontal position to move the grapple into the pile of cane. Due to the inclination of the grapple, the jaws thereof do not engage or dig into the ground and will not pick up dirt and cane trash with the piled cane. Also, due to the full control of the grapple afforded by the operating and supporting mechanisms, the grapple does not engage the piling mechanism or the ground. As the grapple is lowered into the piled cane, the jaw 94 moves into the area between mounds 14 to grasp and engage a substantial portion of the pile. When a sufficient portion of the pile is disposed within the jaws of the grapple, for example to fill the grapple, the vehicle operator closes the jaws 94 and 96 thereof by operation of the hydraulic means 100 and 102, and puts into operation the hydraulic means 78 to pivot the mast to the desired side of the vehicle on which cane is being loaded to trucks or carts, as well as admitting hydraulic pressure to the boom 82 to raise the boom sufficiently so that the grapple will pass over the sides of the truck or cart being loaded. The loading apparatus 68 then may be operated by the vehicle operator to place the load of cane within the body of the truck or the like being loaded, as by lowering the boom and releasing jaws 94 and 96. It should be noted, however, that the depending arm 92 may be pivoted inwardly or outwardly of the boom or the mast 70 pivoted about its mounting to aid the operator to place the load of cane in a desired position in the truck, without having to have the truck placed in exactly the right position with respect to the loader and piler 10.

It is to be noted that the forward progress of the vehicle may be continued during the loading operation as the grapple in grasping the pile of cane is at all times in front of the kicker bars (with respect to the motion of the piler toward the cane) and any cane not picked up by the grapple is lifted and rolled in the direction of the cane yet to be piled. The tilting or inclining of depending bar 92 with respect to the boom and the kicker bars allows the grapple to grasp a large portion of cane piled by the kicker bars without the jaws of the grapple digging into the ground or entering into or between the elements of the piler apparatus. Moreover, the longitudinal axis of the bar 92 and the boom 82 always remains in the same vertical plane, and the grapple, by nature of its mounting, does not swing or oscillate about a vertical axis with respect to the boom; these factors give the vehicle operator complete control over the motion of the grapple, something which has heretofore been lacking in cane loaders of prior practices.

While the mast 70 is shown and described as being mounted directly over the center of the left hand wheel 24, it may be positioned somewhat away from its illus-

trated location with substantially the same results; however, I have found that the support provided by the tractor 16 is most effective during operation of the loading apparatus 20 when the mast 70 is mounted as shown. I comprehend that the mast could be mounted over the right hand wheel in the embodiment shown, if so desired, but in any case the loading apparatus should be so positioned as to readily cooperate with the kicker bars 32. Also, it is to be observed that other mechanisms will occur to those skilled in the art to afford the particular capabilities of full control and inclination of the grapple in the manner described, which capabilities are the primary purpose of the cane loading means. Suitable counterbalancing means (not shown) may be employed, if so desired, to avoid tilting of the vehicle as the loaded boom is swung to the side thereof.

The foregoing description and the drawings are given merely to explain and illustrate my invention, and the invention is not to be limited thereto, except in so far as the appended claims are so limited, since those skilled in the art who have my disclosure before them will be able to make modifications and variations therein without departing from the scope of the invention.

I claim:

1. A cane piling machine comprising a vehicle including frame means carrying a plurality of kicker bars positioned to engage cut cane on motion of the machine toward the cane, link means pivotally connected to the upper end of each of said kicker bars and pivotally connected to said frame means, said link means supporting said kicker bars in generally vertical disposition and accommodating curvilinear generally vertical reciprocating movement of said kicker bars, and actuating means operatively connected to said kicker bars in spaced relation to said link means for moving said kicker bars in curvilinear generally vertical reciprocating movement, said kicker bars each engaging the cane only upon upward forward movement thereof to lift and roll the cane into a pile and being retracted from the cane upon the downward rearward movement thereof.

2. A cane piling machine comprising a vehicle carrying a plurality of kicker bars positioned to engage cut cane on motion of the machine toward the cane, said bars being guided adjacent the upper ends thereof in generally vertical disposition for curvilinear generally vertical reciprocating movement, and crank shaft means rotatably supported on the machine and including eccentric throws, each of said bars including a portion intermediate its ends journaled on an eccentric throw of said crank shaft means to be moved in a curvilinear generally vertical reciprocating movement upon rotation of said crank shaft means, said kicker bars each engaging the cane only upon upward forward movement thereof to lift and roll the cane into a pile and being retracted from the cane upon the downward rearward movement thereof.

3. A cane piling machine comprising a vehicle including frame means carrying a plurality of kicker bars positioned to engage cut cane on the motion of the machine toward the cane, link means pivotally connected to the upper ends of each of said kicker bars and pivotally connected to said frame means, said link means supporting said kicker bars in generally vertical disposition and accommodating curvilinear generally vertical reciprocating movement of said kicker bars, and crank shaft means rotatably supported on the machine and including circumferentially spaced eccentric throws, each of said bars including a portion intermediate its ends journaled on an eccentric throw of said crank shaft means to be moved in a curvilinear generally vertical reciprocating movement upon rotation of said crank shaft means, said kicker bars each engaging the cane only upon upward forward movement thereof to lift and roll the cane into a pile and being retracted from the cane upon the downward rearward movement thereof.

4. A cane piling machine comprising a frame unit carrying a plurality of upright kicker bars to engage cut cane upon motion of the frame unit toward the cane, said bars being provided with cane engaging means on the forward vertical edges thereof, means guidably mounting the kicker bars adjacent the upper ends thereof, said means mounting said bars for forward, upward, rearward and downward movement of at least the lower ends thereof and accommodating a maximum horizontal movement at the lower ends of the bars so that cut cane on the ground is kicked upwardly by the action of the bars during their upward and forward movements.

5. A cane piling machine comprising a frame unit carrying a plurality of upright kicker bars for engagement with cut cane upon motion of the frame unit toward the cane, means guidably mounting the kicker bars adjacent the upper ends thereof, said means mounting said bars for forward and upward movement of at least the lower ends thereof for bringing the lower ends of said bars into engagement with cut cane lying on the ground and enabling them to kick the said cane upwardly and cause the cane to be piled by virtue of the action of the bars and the forward motion of the unit, said means also mounting the bars for subsequent rearward and downward movement to retract the bars from the cane preparatory to subsequent upward and forward contact with cut cane, and means adjacent but spaced from the lower ends of said bars for effecting such movement of said bars.

20 6. A cane piling machine comprising a frame unit carrying a plurality of upright kicker bars to engage cut cane upon motion of the frame unit toward the cane, means guidably mounting the kicker bars adjacent the upper ends thereof, said means accommodating forward-upward and then rearward-downward movement of at least the lower ends of said bars and accommodating substantial horizontal movement of the bars at the lower ends thereof, and drive means operatively connected to said bars in spaced relation to the lower ends thereof to 25 impart a fast forward-upward movement to the lower ends of said bars whereby said bars kick cut cane lying on the ground upwardly into a pile during their forward-upward movement, said drive means subsequently moving said bars rearwardly and downwardly and retracting the same from the piled cane.

45 7. A cane piling machine comprising a frame unit carrying a plurality of upright kicker bars for engagement with cut cane upon motion of the frame unit toward the cane, said bars including cane engaging projections along the forward vertical edges thereof, means guidably mounting the kicker bars adjacent the upper ends thereof, said means accommodating forward and upward movement of at least the lower ends of said bars, and drive means operatively connected to said bars in spaced relation to the lower ends thereof for moving the lower ends of said bars in a direction predominantly forward and also upward for causing said bars to kick the cut cane upwardly into a pile and to remove trash from the cane, said mounting means and said drive means respectively 50 55 60 65 70 75 mounting and driving the bars for subsequent rearward and downward movement to retract the bars from the piled cane and again dispose the same for upward and forward movement.

8. A cane piling machine comprising a frame unit carrying a plurality of upright kicker bars for engagement with cut cane upon motion of the frame toward the cane, means guidably mounting said kicker bars adjacent the upper ends thereof, said means mounting said bars for forward and upward movement of at least the lower ends thereof and accommodating at the lower ends of said bars a forward movement substantially exceeding upward movement, said movement enabling said bars to kick cut cane lying on the ground upwardly into a pile, said means also mounting the bars for subsequent rearward and downward movement to retract

the bars from the piled cane preparatory to subsequent upward and forward contact with cut cane, and means disposed in spaced relation to the lower ends of said bars and operatively connected thereto for effecting such movement of at least the lower ends of said bars.
